UNITED STATES PATENT OFFICE.

JOHN HOWARD ABERNETHY, OF DANVILLE, VIRGINIA.

TELEGRAPHIC TRANSMITTING DEVICE.

1,168,696.

Specification of Letters Patent.

Patented Jan. 18, 1916.

Application filed April 17, 1915. Serial No. 22,170.

To all whom it may concern:

Be it known that I, JOHN H. ABERNETHY, a citizen of the United States, residing at Danville, in the county of Pittsylvania and State of Virginia, have invented a new and useful Telegraphic Transmitting Device, of which the following is a specification.

The present invention appertains to telegraphic transmitters, and aims to provide a novel and improved telegraphic transmitting device of such construction and operation that a series of dots may be produced by a single operation of the device.

It is the object of the invention to provide a transmitter which enables the messages to be quickly and effectively transmitted, a plurality of dots being made by a single operation of the transmitter, and the transmitter having its parts so arranged that there will be no liability of the dots and dashes interfering, or in other words, it is the object of the invention to so construct the transmitter as to avoid the liability of "dot splitting" or "dash jamming."

25 A salient feature of the invention resides in the fact that the device is so constructed, that the contacts which coöperate for producing the dots are moved toward one another when the dots are to be produced, and are separated to a safe distance when the dashes are produced, and conversely, the contacts which coöperate to produce the dashes are separated when the dot producing contacts are moved toward one another. This reduces to a minimum or nullity, the liability of "dot splitting" or "dash jamming" occurring.

It is also within the scope of the invention to provide a transmitting device having the features above noted, and which will not be objectionably complicated or expensive in construction, but which on the other hand may be readily and inexpensively manufactured, the device being thoroughly convenient to operate, and being efficient and serviceable in use.

With the foregoing and other objects in view which will appear as the description proceeds, the invention resides in the combination and arrangement of parts and in the details of construction hereinafter described and claimed, it being understood that changes in the precise embodiment of the invention herein disclosed can be made within the scope of what is claimed, with-

out departing from the spirit of the invention.

The invention is illustrated in its preferred embodiment in the accompanying drawings, wherein:

Figure 1 is a plan view of the improved transmitting device, portions being broken away. Fig. 2 is a cross section taken on the line 2—2 of Fig. 1. Fig. 3 is a side elevation of the device, portions being broken away. Fig. 4 is a cross section taken on the line 4—4 of Fig. 1.

In carrying out the invention, there is provided a suitable base 1 of metal or other material which is a conductor of electrical energy, and which is preferably of rectangular contour. An upstanding yoke or arch 2 is secured upon the base 1 adjacent one end thereof, and a stirrup 3 is pivoted within the yoke 2. To this end, the upper and lower portions of the stirrup 3 are pivoted, as at 4, to the upper portion of the yoke and upper surface of the base 1, respectively. The base 1 is preferably supported by insulating feet or studs 1^a. An actuating lever 5 has its intermediate portion secured within the stirrup 3, and finger pieces 6 are secured in any suitable manner to the forward end or arm of the lever 5.

An oscillatory arm 7 has one end pivoted by means of a pin or pivot element 8 to the stirrup 3 at one side of the lever 5, the arm 7 projecting away from the finger pieces 6, and a screw or stem 9 has one end engaged to the arm 7 and projects loosely through an aperture 10 formed in the rear arm of the lever 5. The free end of the screw or stem 9 has a head 11 and a coiled wire expansion spring 12 is disposed between the head 11 and lever 5 for normally and yieldably swinging the arm 7 toward the rear arm of the said lever 5.

The base 1 carries a standard 13 at that side of the arm 7 opposite the lever 5, and a screw or stem 14 is threaded or adjustably engaged through the standard 13 and projects toward the arm 7. A coiled wire expansion spring 15 is disposed upon the free end portion of the screw or stem 14. One end of the spring 15 bears against the arm 17, and the other end of the spring 15 bears against an adjustable nut 16 threaded upon the screw 14. The nut 16 may be adjusted for regulating the tension of the spring 15 as desired, and the spring 15 serves

to swing the arm 7 toward the lever 5. The screw or stem 14 also limits the movement of the arm in one direction.

A second standard 17 is carried by the base 1 at that side of the arm 7 opposite the standard 13, and an adjustable screw or stop 18 is threadedly or otherwise adjustably engaged through the standard 17 so that its free end projects adjacent the free end of the arm 7. The free end of the arm 7 projects beyond the respective end of the lever 5, and normally bears against the screw or stop 18. The spring 15 normally moves the arm 7 against the screw or stop 18. The arm 7 is thus arranged to swing a limited amount between the screws or stops 14 and 18.

A standard 19 is carried by a block of insulation 20 embedded in the base 1, whereby the standard 19 is insulated from the base, and a lever 21 is fulcrumed intermediate its ends upon the standard 19. The forward arm of the lever 21 is connected by means of a link 22 to the rear arm of the actuating lever 5, the link 22 being of insulating material whereby the lever 5 and corresponding parts are insulated from the lever 21 and standard 19. The link 22 works loosely through an opening 22^a formed in the arm 7, whereby the link 22 and arm 7 do not interfere with one another.

The rear arm of the lever 21 has a contact 23 which co-operates with a screw or contact 24 threadedly or adjustably engaged through an upstanding standard 25 carried by the base 1.

A switch 26 is pivoted or fulcrumed upon the base 1 and is engageable under a contact 27 carried by the standard 19, whereby the standard 19 may be electrically connected with the base 1 by means of the switch 26 when it is desired to normally close the circuit for cutting out the transmitting device.

A vibrator bar 28, which is approximately in alinement with the arm 7, is connected to the arm 7 by means of a flat vertical spring 29. One end of the spring 29 is secured to or within the free end of the arm 7, and the other end of the spring 29 is secured to or within the adjacent end of the bar 28, whereby the bar 28 is supported for horizontal vibratory movement by the spring 29, but is supported above the base by the spring 29 so that the vibratory bar 28 will not be liable to interfere with the base.

An adjustable weight 30 is slidably mounted upon the bar 28, and is provided with a set screw 31 for clamping it in position upon the bar 28. The weight 30 is provided with a recess 32 at one side, and pins 33 are engaged through the weight 30 and extend across the recesses 32, to engage the bar 28 for holding the weight 30 slidably upon the bar.

The recess 32 accommodates a resilient or

flexible contact strip or leaf spring 34, which is secured at one end to the free end of the bar 28, as at 35, and the spring strip 34 projects along one side of the bar 28 toward the other end thereof. The recess 32 receives the spring strip 34 and allows said strip to vibrate therein. The free or forward end portion of the strip 34 is bent back, as at 36, and the bent back or free end portion 36 of the strip 34 is provided with a contact 37 which is co-operable with the contact 38 carried by one end of a screw or adjustable member 39 engaged through the rear arm of the lever 21.

A screw or adjustable stop 40 is engaged through the bar 28 adjacent its forward end and serves to limit the movement of the spring strip 34 toward the bar 28.

The movement of the vibratory bar 28 away from the lever 21 is limited by means of a screw or adjustable stop 41 engaged through a standard 42 carried by the base, the free end of the screw 41 having a buffer 43 thereon against which the free end of the bar 28 is arranged to bear when the bar 28 moves away from the lever 21.

It will be noted that the screw 9, screw 14, screw 18, screw 40, screw 39, screw 24, screw 41 and weight 30 may each be adjusted in order that the device will operate properly. One line or conductor of the circuit is connected to the base 1 and will therefore be in electrical connection with the post 25 and its screw or contact 24, as well as being in electrical connection with the contact 37 through the medium of the strip 34, bar 28, spring 29, lever 5, and stirrup 3. The lever 21 is insulated from the base, and the other wire or conductor of the circuit is connected to the post 19. When it is desired to cut off the transmitting device from the circuit, the switch 26 may be closed or swung into engagement with the contact 27, which will connect the base and post 19 for the intended purpose. During the operation of the transmitting device, the switch 26 is swung open, so as to disconnect the base and post or standard 19.

Presupposing that the operator is facing that end of the transmitter having the finger pieces 6, when it is desired to produce one or a series of dots, the finger pieces 6 are moved to the right, as viewed in Fig. 1, and the rear arm of the lever 5 will thus be swung to the left. This will cause the rear arm of the lever 5 to contact with the arm 7 and swing said arm to the left. The vibrator 28 will thus be swung sharply to the left. Due to the fact that the rear arm of the lever 5 is swung to the left, the forward arm of the lever 21 will also be swung to the left through the medium of the link 22, and the rear arm of the lever 21 which carries the contact 38 will be swung toward the right. It will therefore be evident that

the coöperating contacts 37 and 38 which produce the dots are moved toward one another when the finger pieces 6 are moved toward the right for producing the dot or dots. The vibrator 28 being set in motion will vibrate between the buffer 43 and contact 38, and each vibration of the vibrator will cause the contact 37 of the vibrator to engage the contact 38 of the lever 21 for producing a dot. When the contacts 37 and 38 engage one another, the circuit is closed between the standard 19 and base 1, through the lever 21, contact 38, contact 37, strip 34, bar 28, spring 29, arm 7 and stirrup 3. The vibrator 28 not only vibrates, but the contact strip 34 also vibrates to assist in the rapid and effective production of the dots. The number of dots produced is governed by the length of time that the finger pieces 6 are held to the right, so that either a single dot or a series of dots may be quickly produced. When the required number of dots are produced, the finger pieces 6 are released, and as a result the spring 15 will swing the arm 7 back to normal position against the stop 18, and this will cause the vibrator 28 to swing back to initial position, and at the same time the lever 21 will also swing back to normal position. The contacts 37 and 38 are thus quickly and effectively separated. Thus, as soon as the desired number of dots are produced the coöperating dot producing contacts may be separated to such a distance that there is no liability for the transmitter to produce an excessive dot or dots.

In order to produce one or more dashes, the dashes being made one at a time, the finger pieces 6 are moved to the left, as seen in Fig. 1, and the rear arm of the lever 5 being thereby moved to the right will cause the link 22 to pull the forward arm of the lever 21 to the right. This will swing the rear arm of the lever 21 to the left to bring the contact 23 of the lever 21 into engagement with the screw or contact 24 for closing the circuit. The finger pieces 6 are held to the left a sufficient time to produce a dash impulse in the circuit, and the finger pieces 6 are then released so as to separate the contacts 23 and 24. When the dash is being produced, the vibrator 28 will remain inactive or passive, since the rear arm of the lever 5 being moved to the right, cannot move the arm 7, because the arm 7 bears against the screw or stop 18. The spring 12 is brought under greater compression or tension when the rear arm of the lever 5 is swung to the right, so that the spring 12 returns the lever 5 to normal or intermediate position when the finger pieces 6 are released after having been moved to the left. Therefore, by properly manipulating the finger pieces 6, various codes may be followed, the finger pieces 6

being moved to the right when a dot or series of dots are desired and being moved to the left when a dash is to be produced. The transmitter enables the dots and dashes to be quickly and effectively produced, and will eliminate the possible occurrence of "dot splitting" or "dot jamming."

From the foregoing, taken in connection with the drawings, it is believed that the advantages and attributes of the present apparatus will be obvious to those skilled in the art, without further comment being necessary.

Having thus described the invention, what is claimed as new is:—

1. In a telegraphic transmitting device, a vibrator having a contact, means for actuating said vibrator, a contact operable with the aforesaid contact, and means for moving the second mentioned contact toward the first mentioned contact when the vibrator is set in motion, and for normally moving the second mentioned contact away from the first mentioned contact.

2. In a telegraphic transmitting device, a vibrator, means for setting the same in motion, a contact carried by the vibrator, a second contact, a movable member having a contact coöperable with the second contact and a contact coöperable with the first mentioned contact, and means operatively connecting said member and said means, whereby when said means is actuated for setting the vibrator in motion the fourth mentioned contact is moved toward the first mentioned contact, while the other contacts are separated, said means being operable for swinging the second contact and third mentioned contacts into engagement and whereby the fourth mentioned contact will be moved away from the first mentioned contact.

3. In a telegraphic transmitting device, an actuating lever, a vibrator operatively connected to said lever to be set in motion thereby and having a contact, a second lever having a contact coöperable with the first mentioned contact, and an operative connection between the two levers, whereby when the actuating lever is moved for setting the vibrator in motion the second lever will be swung to move its contact toward the first mentioned contact.

4. In a telegraphic transmitting device, an actuating lever, a vibrator operatively connected thereto to be set in motion thereby and having a contact, a second lever having a contact coöperable with the aforesaid contact and another contact, a fourth contact coöperable with the third mentioned contact, and an operative connection between the two levers, whereby when the actuating lever is swung in one direction for setting the vibrator in motion the second lever will be swung to move the second mentioned con-

- tact toward the first mentioned contact and to move the third mentioned contact away from the fourth mentioned contact, and whereby when the actuating lever is swung in the other direction the second mentioned contact will be moved away from the first mentioned contact while the third mentioned contact is moved into engagement with the fourth mentioned contact.
- 10 5. In a telegraphic transmitting device, an actuating lever, an oscillating arm arranged to be engaged and swung by the actuating lever when the actuating lever is swung in one direction, a vibrator carried by said arm and having a contact, spring means for moving said arm toward said lever, a stop against which said arm is seatable under the influence of said spring means, a second lever having a contact coöperable with the aforesaid contact and another contact, a link connecting the two levers whereby when the actuating lever is swung in the said direc-

tion the second mentioned contact will be moved toward the first mentioned contact and when the actuating lever is swung in 25 the other direction the second mentioned contact will be moved away from the first mentioned contact, a fourth contact coöperating with the third mentioned contact whereby when the actuating lever is swung 30 to move the second mentioned contact away from the first mentioned one, the third mentioned contact will be moved toward the fourth mentioned contact, and spring means between said actuating lever and arm tending to move the actuating lever and arm together.

In testimony that I claim the foregoing as my own, I have hereto affixed my signature in the presence of two witnesses.

JOHN HOWARD ABERNETHY.
